UNITED STATES PATENT OFFICE.

FREDERICK WILLIAM PARSONS, OF CLEVELAND, OHIO.

SHIRT-COLLAR.

No. 824,577.

Specification of Letters Patent.

Patented June 26, 1906.

Application filed March 6, 1905. Serial No. 248,419.

To all whom it may concern:

Be it known that I, FREDERICK WILLIAM PARSONS, a citizen of the United States, residing at Cleveland, in the county of Cuyahoga and State of Ohio, have invented certain new and useful Improvements in Shirt-Collars; and I do declare that the following is a full, clear, and exact description of the invention, which will enable others skilled in the art to which it appertains to make and use the same.

My invention has reference to improvements in shirt-collars of the lay-down or turn-down variety, and my improved collar is so constructed that it becomes comparatively easy to button the collar at the back of the neck and to disengage the collar from the button, all substantially as shown and described, and particularly pointed out in the claim.

In the accompanying drawings, Figure 1 is a perspective view of the collar in one form of my invention; and Fig. 2 is a cross-section thereof centrally across its rear.

It is a common and well-known objection to lay-down collars that the collar-band lies so snugly in front of and next to the turn-down or lay-down portion outside that it is exceedingly difficult to engage the collar upon the button at the back of the neck. This difficulty is of such universal experience that it need not be especially emphasized here, and it is the object of this invention to remedy the said difficulty and provide a collar in which engagement with the collar-button at the back is rendered comparatively easy. This is accomplished in this instance by means of a tongue or flap, which is practically independent of the collar so far as handling the same in buttoning and unbuttoning is concerned, but which is integral with the collar-band at its top. Thus in the figures, C represents the collar in its entirety, and B the neckband. Now in order that the collar may be provided with the benefits of my invention I cut out a portion of the band at two places at its rear from its lower edge upward about one-half or slightly more of the depth of the band and produce a depending tongue or projection c at the middle of the collar, containing the buttonhole and adapt-

ed to be separately swung inward for making engagement and disengagement with the button—that is, the said tongue or strip is handled alone in buttoning independently of the collar by inserting the fingers more or less through the said openings or recesses 2, so as to reach the buttonhole and button behind the tongue, thus making connection with the button through buttonhole 3 without opening the collar and, in fact, without inconvenience, especially on account of the starched and rigid and otherwise closed condition of the collar. This also brings the tongue or flap c on the inside of the collar, where it is not noticeable nor objectionable in any way, and the collar is held as securely in place as it would be if it were made in the old way.

It is to be observed that the collars are stiff, and the buttoning and unbuttoning occurs while the collar is about the neck, and may even be buttoned at the front, hence the necessity of having recesses 2 in the band of such width that room is afforded on each side of tongue c to freely introduce the fingers from either side and press the said tongue inward from the lay-down portion independently of the band of the collar when buttoning and unbuttoning takes place.

What I claim is—

As a new article of manufacture, a lay-down collar having a neckband provided with two cut-out portions at its rear forming open recesses extending from the lower edge thereof upward approximately half the depth of said band, said recesses having their greatest width at the bottom and converging upward, and a tongue integral with the band between said recesses and provided with a buttonhole, whereby said recesses provide room to enable the fingers to be freely introduced to press the tongue inwardly independently of the remainder of the collar during buttoning and unbuttoning, said band having a continuous uncut surface from said recesses to the ends thereof.

In testimony whereof I sign this specification in the presence of two witnesses.

FREDERICK WILLIAM PARSONS.
